UNITED STATES PATENT OFFICE.

GEORGE ODUM, OF CHICAGO, ILLINOIS.

DEVICE FOR SMOOTHING OR DRESSING RAILS.

Application filed December 18, 1924. Serial No. 756,693.

To all whom it may concern:

Be it known that I, GEORGE ODUM, a citizen of the United States, residing at Chicago, in the county of Cook and State of Illinois, have invented a new and useful Improvement in Devices for Smoothing or Dressing Rails, of which the following is a specification.

This invention relates to improvements in devices for smoothing or dressing rails; and is here shown as embodied in a device particularly applicable for use in connection with smoothing or dressing rails such as are used, for example, for carrying traveling cranes, ore bridges, and similar heavy loading and unloading devices or other machinery or apparatus supported on carriages operating on rails.

The rails used in connection with such devices which usually are quite heavy, frequently quickly develop beads, fins or protruding edges at the margins of their upper surfaces as a result of the loads carried by them. For various reasons it frequently is desirable or necessary that the rails be smoothed or dressed by removing these beads, fins, feather edges, or protruding edges therefrom.

By the use of my invention, the rails may be smoothed or dressed without removing them from their position in the track, that is, in situ. By the use of my invention, also, the work may be easily and cheaply done; and the device for accomplishing the same may be quickly and cheaply made, and is simple in operation and durable.

The device is adapted for attachment to the carriage of the traveling crane, or bridge or other apparatus running on the rails to be smoothed; and is adapted to operate on the rail with the movement of said carriage.

Other features and advantages of my invention will appear more fully as I proceed with my specification.

In that form of device embodying the features of my invention shown in the accompanying drawings, Figure 1 is a view partly in side elevation and partly in vertical section, of one of the devices, it being understood that there is one of such devices for each rail to be operated upon, Fig. 2 is a view taken as indicated by the line 2-2 of Fig. 3, and Fig. 3 is a view of the device in end elevation.

As shown in the drawings, 10 indicates one of the rails adapted to be smoothed or

dressed. 11 indicates a part of the frame of the carriage carrying the crane, bridge or other apparatus running on the rails 10. This part of the carriage is here shown as 60 a channel member having a horizontal flange at its lower edge.

12 indicates a U-shaped tool holder of bar steel or other suitable material supported on a pivot bolt 13 which is fastened to the 65 bracket 14 which in turn is bolted as by means of the bolts 15, or otherwise secured, to the carriage 11 of the crane or other apparatus.

The upper end of the member 12 is provided with a rectangular shaped slot 16 in which there is mounted the cross head 17 which is vertically slidable in said slot. The pivot pin 13 extends through this cross head, 18 and 19 indicating suitable bushings. 70 The up and down adjustment of the cross head 17 is effected by means of the screws 20 and 21. Since the cross head 17 is pivotally mounted on the pin 13, it will be seen that by adjusting the set screws 20 and 21, 80 the member 12 may be raised or lowered.

The member 12, which is the tool carrier, supports opposed cutting tools 22 and 23, one lying on each side of the rail 10 and adapted to remove the feather edge or bead 85 from each margin of the upper surface. In Fig. 2, these beads as the same are cut off by the tools 22 and 23, are indicated by 24, 24. The cutting tools 22 and 23 are adjusted by means of the screws 25 and 26, respectively, and are adapted to be firmly clamped in any position by means of the dogs 27 and 28, respectively, which are held by means of the nuts 29 and 30, respectively.

The tool holder is held in its proper relation to the sides of the rail by the opposed guide screws 31 and 32. The inner end of each of these guide screws is provided with a ball bearing where it contacts with the side of the rail. The ball bearing on screw 31 is indicated by 33, and it is to be understood that guide screw 32 has a similar ball bearing contacting with the other side of the rail.

A draw rod 34 is also provided which has its forward end attached to a bracket 35 fastened to the member 11. The rear end of the draw rod 34 is bifurcated as indicated by 36, the two ends of the bifurcated part being pivotally secured to the ends of a pin 110 37 extending through the tool holder 12 as shown.

In operation, the device is secured to the frame 11 by means of the brackets 14 and 35 as shown, and the cutters 22 and 23 and the guide screws 31 and 32 are adjusted so that the proper depth of cut will be made to take off any bead or feather edge on the sides of the upper surface of the rail 10. The height of the cutting tools is adjusted by means of the screws 20 and 21. The pivotal mounting of the tool holder 12 on the pivot pin 13 is provided because of the usual side play present in the movement of the cranes or bridges on the rails. The flanged wheels supporting the bridge or crane on the rails frequently permit up to a couple of inches of side play in their movement. Such side play does not affect the operation of the cutting device because the guide screws 31 and 32 will keep the cutting tools in the proper position and the necessary relative sideways motion with respect to the member 11 is permitted by means of the pivot 13. The draw rod 34 has sufficient lost motion where it is attached to the bracket 35, or is sufficiently flexible, or both, to permit the necessary pivoting on the pivot 13.

The draw rod 34 exerts a pull on the tool carrier 12 near its lower end and thus removes the strain that otherwise would be put on the pivot 13 during the cutting operation.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as possible in view of the prior art.

What I claim as new and desire to secure by Letters Patent, is:

1. In combination with a crane, bridge, or the like, having a carriage travelling on rails; a tool holder attached to said carriage; and a cutting tool mounted in said tool holder and adapted to engage the margin of the upper surface of one of the rails and smooth or dress the same as said carriage moves.

2. In combination with a crane, bridge, or the like, having a carriage travelling on rails; a tool holder pivotally attached to said carriage whereby lateral swinging movement of the lower end of said tool holder is permitted; and a cutting tool mounted in the lower end of said tool holder and adapted to engage the margin of the upper surface of one of the rails and smooth or dress the same as said carriage moves.

3. In combination with a crane, bridge, or the like, having a carriage travelling on rails; a tool holder attached to said car-

riage; and opposed cutting tools mounted in said tool holder and adapted to engage the margins of the upper surface of one of the rails and smooth or dress the same as said carriage moves.

4. In combination with a crane, bridge, or the like, having a carriage travelling on rails; a tool holder pivotally attached to said carriage whereby laterally swinging movement of the lower end of said tool holder is permitted; and opposed cutting tools mounted in the lower end of said tool holder and adapted to engage the margins of the upper surface of one of the rails and smooth or dress the same as said carriage moves.

5. In combination with a crane, bridge, or the like, having a carriage travelling on rails; a tool holder attached to said carriage; a cutting tool mounted in said tool holder and adapted to engage the margin of the upper surface of one of the rails and smooth or dress the same as said carriage moves; and guiding members carried by the tool holder and adapted to engage the sides of the rail being smoothed or dressed to hold the cutting tool in proper cutting position.

6. In combination with a crane, bridge, or the like, having a carriage travelling on rails; a tool holder pivotally attached to said carriage whereby lateral swinging movement of the lower end of said tool holder is permitted; a cutting tool mounted in the lower end of said tool holder and adapted to engage the margin of the upper surface of one of the rails and smooth or dress the same as said carriage moves; and guiding members carried by the tool holder and adapted to engage the sides of the rail being smoothed or dressed to hold the cutting tool in proper cutting position.

7. In combination with a crane, bridge, or the like, having a carriage travelling on rails; a tool holder attached to said carriage; opposed cutting tools mounted in said tool holder and adapted to engage the margins of the upper surface of one of the rails and smooth or dress the same as said carriage moves; and guiding members carried by the tool holder and adapted to engage the sides of the rail being smoothed or dressed to hold the cutting tools in proper cutting position.

8. In combination with a crane, bridge, or the like, having a carriage travelling on rails; a tool holder pivotally attached to said carriage whereby lateral swinging movement of the lower end of said tool holder is permitted; opposed cutting tools mounted in the lower end of said tool holder and adapted to engage the margins of the upper surface of one of the rails and smooth or dress the same as said carriage moves; and guiding members carried by the tool

holder and adapted to engage the sides of the rail being smoothed or dressed to hold the cutting tools in proper cutting position.

9. In combination with a crane, bridge, or the like, having a carriage travelling on rails; a tool holder pivotally attached to said carriage whereby lateral swinging movement of the lower end of said tool holder is permitted; a cutting tool mounted

10 in the lower end of said tool holder and adapted to engage the margin of the upper surface of one of the rails and smooth or dress the same as said carriage moves; and means for adjusting said tool holder vertically.

11. In combination with a crane, bridge, or the like, having a carriage travelling on rails; a tool holder attached to said carriage; a cutting tool mounted in said tool holder and adapted to engage the margin of the upper surface of one of the rails and smooth or dress the same as said carriage moves; and means for adjusting said tool holder vertically.

12. In combination with a crane, bridge, or the like, having a carriage travelling on rails; a tool holder attached to said carriage; opposed cutting tools mounted in said tool holder and adapted to engage the margins of the upper surface of one of the rails and smooth or dress the same as said carriage moves; and means for adjusting said tool holder vertically.

13. In combination with a crane, bridge, or the like, having a carriage travelling on rails; a tool holder attached to said carriage; a cutting tool mounted in said tool holder and adapted to engage the margin of the upper surface of one of the rails and smooth or dress the same as said carriage moves; means for adjusting said tool holder vertically; and a draw bar having one end attached to the lower end of said tool holder and the other end attached to said carriage.

14. In combination with a crane, bridge, or the like, having a carriage travelling on rails; a bracket attached to said carriage; a pivot pin on said bracket; a cross-head pivotally mounted on said pivot pin; a tool holder carried by said cross-head and adapted for vertical sliding adjustment thereon; and a cutting tool mounted in said tool holder and adapted to engage the margin of the upper surface of one of the rails and smooth or dress the same as said carriage moves.

15. In combination with a crane, bridge, or the like, having a carriage travelling on rails; a bracket attached to said carriage;

16. In combination with a crane, bridge, or the like, having a carriage travelling on rails; a bracket attached to said carriage; a pivot pin on said bracket; a cross-head pivotally mounted on said pivot pin; a tool holder carried by said cross-head and adapted for vertical sliding adjustment thereon; and opposed cutting tools mounted in said tool holder and adapted to engage the margins of the upper surface of one of the rails and smooth or dress the same as said carriage moves.

17. In combination with a crane, bridge, or the like, having a carriage travelling on rails; a bracket attached to said carriage; a pivot pin on said bracket; a cross-head pivotally mounted on said pivot pin; a tool holder carried by said cross-head and adapted for vertical sliding adjustment thereon; a cutting tool mounted in said tool holder and adapted to engage the margin of the upper surface of one of the rails and smooth or dress the same as said carriage moves; and a draw bar having one end attached to the lower end of said tool holder and the other end attached to said carriage.

Witness my hand and seal this 1 day of December, 1924.

GEORGE ODUM. [L.S.]
